UNITED STATES PATENT OFFICE

91,106

DESIGN FOR A TILE BAR

N. Ralph Faire, New York, N. Y.

Application April 17, 1933. Serial No. 47,815

Term of patent 7 years

To all whom it may concern:

Be it known that I, N. RALPH FAIRE, a citizen of the United States, residing in the Borough of Queens, county of Queens, city and State of New York, have invented a new, original, and ornamental Design for a Tile Bar, of which the following is a specification, reference being had to the accompanying drawing, forming part thereof.

Fig. 1 is a front elevation of a tile bar showing my new design;

Fig. 2 is an end elevation of said bar, and

Fig. 3 is a rear perspective view of my said bar.

I claim:

The ornamental design for a tile bar as shown.

N. RALPH FAIRE.
